UNITED STATES PATENT OFFICE.

TONJES A. BOTH, OF STRATFORD, CONNECTICUT, ASSIGNOR TO THE CONNECTICUT ELECTRIC MANUFACTURING COMPANY, OF BRIDGEPORT, CONNECTICUT, A CORPORATION OF CONNECTICUT.

MOUNTING FOR ELECTRICAL DEVICES.

Application filed March 24, 1924. Serial No. 701,414.

This invention relates especially to a means for mounting face plates or similar members of electrical devices, and has for an object to provide a mounting for this type of devices 5 which may be entirely insulated so that there will be no danger of the user being injured by touching a ground.

It is also an object of the invention to provide improved securing means for these face 10 plates and the like, which will securely hold the plate in proper position, and may be so arranged as to allow adjustment of the plate so that it may be properly located, and which will also give a neat, attractive and finished 15 appearance to the completed installation.

With the foregoing and other objects in view, I have devised the construction illustrated in the accompanying drawing, which shows the preferred construction for employing 20 the principles of my invention, and which drawings form a part of this specification. In this drawing,

Fig. 1 is a partial side elevation and a partial section showing a receptacle and its face 25 plate in position on the outlet box.

Fig. 2 is a front view thereof looking from the right of Fig. 1.

Fig. 3 is a view similar to Fig. 1 showing how the mounting may be employed for a 30 switch.

Fig. 4 is a front view looking from the right of Fig. 3.

Fig. 5 is a top plan view and a side elevation, partly broken away, showing the construction of the finishing member.

Fig. 6 is a top plan view and a longitudinal section of the securing screw.

Fig. 7 is a detailed section of the securing means substantially on line 7—7 of Fig. 1 and 40 on an enlarged scale, and

Fig. 8 is a plan view of the countersunk opening of Fig. 2 with the securing screw removed.

Referring to Figs. 1 and 2, numeral 10 represents the usual metal wall box in which the electrical devices are mounted. In these figures is shown a receptacle 11 having openings 12 in its front wall leading to spring contacts carried in the receptacle for engagement with 45 the finger contacts of the ordinary caps. The contacts are not illustrated as they may be of any usual construction and form no part of my present invention. In the form shown in Figs. 1 and 2 the body 11 of the receptacle is

made of insulating material and is molded 55 in one piece with the face plate 13, so that the face plate is also of insulating material. For the purpose of securing the face plate and the receptacle over the opening in the wall box, openings 14 are provided in the plate 60 for passage of the securing screws 15. Although I do not wish to be limited to this specific construction, the head 16 of the screw is preferably substantially cylindrical to provide a shoulder 17 on the under side thereof, 65 and the opening through the face plate is countersunk to receive this head. Although it may not be necessary in all cases, the opening 12 and its countersunk are preferably 70 elongated somewhat, as shown in Fig. 2, so that the plate and the receptacle may have a certain amount of lateral adjustment to insure its location in proper position, it being well known that the wall boxes are usually 75 not accurately positioned in the wall. It will thus be apparent, that when the securing screw is passed through the opening in the plate and threaded into the ears 18 of the wall box, they may be tightened so that the shoulder 17 will clamp against the bottom wall of 80 the countersink and retain the plate in its adjusted position. It is preferred to make the depth of the countersink substantially the same as the length of the head of the screw 85 so that the outer end of the head will be substantially flush with the face of the plate, but this, of course, may be varied as desired without departing from the spirit of my invention. The screw is, of course, provided with suitable means to coact with a tool for operating 90 it, such as a transverse slot 19.

After the plate has been secured in the proper position, finishing members 20 are removably secured to the screw. These members may be made of different constructions 95 or of different appearances, but it is preferred to use a construction substantially, as shown in Fig. 5, in which there is a body portion of insulating material having suitable ornamentation on its outer surface, such as 100 radial ribs 21, and also has a threaded stud 22 adapted for engagement in a tapped or threaded opening 23 leading from the outer end of the securing screw. The stud 22 is preferably provided with a head 24 molded in the body of the finishing member, so that 105 they are securely fastened together. The finishing member is applied to the screw by

merely threading the stud into the opening 23. The lower surface of the body portion clamps against the face of the face plate, the ribs 21 facilitating the operation of applying 5 or removing this finishing member. The body portion of this member is of sufficient size to cover the head of the screw and also the countersunk portion of the elongated opening in the face plate in any position of the screw in 10 this opening. Thus the finishing member gives a neat and attractive finished appearance, and the body portion thereof being of insulating material removes all possibility of 15 the user placing the finger in contact with a conducting element which may at any time be rendered alive electrically by any defect in the electrical connections or the insulation. It also allows the metal head of the screw to do the holding for the face plate, 20 giving a rigid and reliable securing means for this plate.

Referring to Figs. 4 and 5, I have shown how a similar securing means may be employed for the face plate of a switch or similar device which is separate from the face plate. In the ordinary arrangement of these devices, the switch, the body of which is shown at 25, is mounted on a metal strap or yoke 26 having elongated slots 27 at its opposite ends to receive screws 28 for securing the yoke to the ears 18 of the wall box. The adjustment here is secured by means of these elongated slots in the yoke. The face plate 29 is a separate member but is preferably made 35 of insulating material, and has countersunk openings 30 to receive the securing screws 15, as in the first form, except that these screws are threaded into the yoke 26. As adjustment for the switch and the face plate is allowed by the slots 27 in the yoke, it is not necessary in this layout to have the countersunk openings 30 in the face plate elongated as shown in Fig. 2. Aside from this the use 40 of the securing screws 15 and the finishing member 20 is exactly the same as in the first form.

Having thus set forth the nature of my invention, what I claim is:

1. In an electrical device, a face plate of 50 insulating material adapted to cover the open side of a wall outlet box, a securing means for securing said plate to a support and exposed at the front of the plate, a separate finishing member including a body portion of insulating material, and means to removably 55 secure said member to said securing means, said body portion being of a size to cover said securing means.

2. In an electrical device, an electrically

dead front face plate adapted to cover the 60 open side of a wall outlet box, an electrically conducting securing means for said plate having connection with said box and exposed at the front of the plate, a separate finishing member including a body portion of insulating material, means to removably secure said member to said securing means, said body being of a size to completely cover and insulate 65 said securing means.

3. In an electrical device, a face plate of 70 insulating material adapted to cover the open side of a wall outlet box, securing means extending through said plate and having connection with said box to secure the plate there- 75 to, separate finishing members having body portions of insulating material, and means to removably secure said members to said se- 80 curing means, said body portions being of a size to cover said means.

4. In an electrical device, a face plate of 80 insulating material adapted to cover the open side of a wall outlet box and having a counter- 85 sunk opening therein, a securing screw ex- 90 tending through said opening to secure the plate over said box and provided with a sub- 95 stantially cylindrical head having a shoulder on its under side to engage the bottom of the countersink, said head being also provided with means to coact with a tool to operate said screw and a threaded opening leading from its outer end, and a separate finishing mem- 100 ber having a threaded stud in the opening in the screw and a body portion of insulating material covering the head of the screw.

5. In an electrical device, a face plate of 105 insulating material adapted to cover the open side of a wall outlet box, a securing screw extending through said plate for fastening the plate to said box and having a head pro- 110 vided with means to coact with a tool for ma- 120 nipulating the screw, a separate finishing member, and means to removably secure said member to said screw, said member including a body portion of insulating material covering the head of the screw.

6. In an electrical device, a face plate of 125 insulating material adapted to cover the open side of a wall outlet box, a securing screw extending through said plate for fastening the plate to said box and having a threaded opening leading from the outer end thereof, and a separate finishing member having a threaded stud in said opening and a body portion of insulating material covering the 130 head of the screw.

In testimony whereof I affix my signature.

TONJES A. BOTH.
